[57] CLAIM

The ornamental design for a chair, as shown and described.

DESCRIPTION

FIG. 1 is a perspective view of the chair showing my design;

FIG. 2 is a right side view thereof; and

FIG. 3 is a rear elevational view of the chair of FIG. 1. The left side of the chair is a mirror image of the right side as shown.

FIG. 3

FIG. 2

FIG. 1
